McFerrand & McCready.

UNITED STATES PATENT OFFICE.

CHARLES W. E. CLARKE, OF BROOKLINE, MASSACHUSETTS.

INTERNAL-COMBUSTION ENGINE.

Application filed August 13, 1917. Serial No. 185,819.

To all whom it may concern:

Be it known that I, CHARLES W. E. CLARKE, a citizen of the United States, residing at Brookline, in the county of Norfolk and State of Massachusetts, have invented certain Improvements in Internal-Combustion Engines, of which the following description, in connection with the accompanying drawings, is a specification, 10 like reference characters on the drawings indicating like parts in the several figures.

This invention relates to internal combustion engines and is particularly concerned with the type of engine of this character 15 which is provided with a plurality of inlet and outlet valves for each cylinder. Engines of this type have been used to only a relatively limited extent heretofore but are rapidly going into use particularly for automobile and aeroplane service. The present invention has for its chief object to increase the flexibility of control of engines of this type and also to improve the economy of these engines.

25 The various features of the invention will be readily understood from the following description, reference being made to the accompanying drawings, in which—

Figure 1 is a plan view of those parts of 30 an internal combustion engine necessary to an explanation of the present invention;

Fig. 2 is a view, partly in vertical cross section and partly in side elevation, of the engine shown in Fig. 1; and

35 Fig. 3 is a vertical, transverse, cross sectional view taken on the line 3—3, Fig. 1.

The engine shown is of the four-cycle type and comprises two cylinders, indicated respectively at A and B. Each cylinder is 40 equipped with two inlet valves of the poppet type, indicated at 2 and 3, respectively, and also with two outlet valves, one of which is indicated at 4 in Fig. 3. An inlet manifold 5 leads from the carbureter 6 to the inlet 45 valves of the cylinders and an exhaust manifold 7 conducts the burnt gases away from the outlet valves.

The inlet valves 2 and 3 of each cylinder are operated from a cam shaft 8 carrying a 50 series of cams, two of which are indicated at 9 and 10, Fig. 2, and which co-operate with suitable valve stems 11 to lift the valves 2 and 3 off their seats at the proper times in the cycle of operation of the engine to admit 55 fuel to the cylinder. Springs indicated at 12 hold the valve stems in contact with the

cams 9 and 10 and tend to seat the valves. The outlet valves are operated in a similar manner by a cam shaft 14 lying parallel with the shaft 8 and on the opposite side of the main crank shaft 15 from the shaft 8. In order to rotate the cam shafts 8 and 14, they have secured to their forward ends pinions 16 and 17, respectively, which mesh with a barrel gear 18 mounted fast on the main shaft 15.

In the usual arrangement in engines having four valves per cylinder, as in the construction shown, the two inlet valves open and close simultaneously and the two outlet valves also open and close simultaneously. The valve movement is relatively short so that often the entire port area is not available for the flow of gases into or out of the engine cylinder. In the present arrangement the operating mechanism for the valves is so arranged that the operator can vary the number of valves of each cylinder in operation at any time and can also adjust the length of stroke of the valves. For this purpose the cam 9 which operates the valve 2 is provided with a relatively long cylindrical portion *a* in which the elements of the cam face all lie parallel to the axis of the cam shaft 8; another portion *b* extending forward from the part *a* and having the elements of the rise of the cam, that is the part of the cam that produces the valve-lifting movement, inclined with relation to the axis of the shaft 8; and another part *c* at the end of the part *b* in which the cam face elements all extend parallel to the shaft 8. The cam 10 which operates the valve 3 is provided with similar cam faces *a*, *b* and *c*, but this cam differs from the cam 9 in 95 that the part *a* is very short, about equal in length to the part *c* of the cam 9, while the part *c* of the cam 10 is about equal in length to the part *a* of the cam 9, the inclined parts *b* of both cams being substantially equal in length. This cam shaft is adjustable longitudinally of its axis so that any part *a*, *b* or *c* of either cam 9 or 10 may be made to operate its respective valve 2 or 3.

When the shaft 8 is in the position in which it appears in Fig. 2, it produces no lifting movement of the valve 2 since the valve stem rests on the cylindrical part *a* of the cam 9; but the valve 3 at this time is receiving its maximum valve-opening movement since its valve stem rests on the high-

est part *c* of the cam 10. If this shaft were now moved toward the right, Fig. 2, the inclined part *b* of the cam 10 would be brought under the valve stem and the valve 3 would receive a shorter valve-opening movement as this adjustment proceeded toward the right, while the valve 2 would still remain inoperative. This adjustment would reduce the power produced by the engine 10 since the shorter valve movement would afford less area for the flow of gas into the cylinder than would a longer stroke. If, on the other hand, the shaft 8 were moved to the left, as the parts appear in Fig. 2, then 15 the valve 3 would still continue to open its maximum distance at each rotation of the cam 10, while the valve 2 would be brought into operation due to the fact that the inclined part *b* of the cam 9 would be moved 20 into co-operative relationship to the stem of this valve. If this adjustment of the shaft 8 toward the left were made sufficient to bring the part *c* of the cam 9 under the stem of the valve 2, this valve then would be 25 given its maximum length of stroke while the valve 3 also would continue to make its maximum opening movement at each rotation of the shaft 8. The exhaust valves are similarly operated.

30 For the purpose of effecting this adjustment of the shafts 8 and 14 they are mounted to slide in their bearings in the base of the engine and an adjusting mechanism is provided which comprises a yoke 20 mounted to rock on a rock shaft 21 and having pins or rolls that enter the grooves or collars fixed, respectively, on the shafts 8 and 14, one of which collars is indicated at 22 in Fig. 2. A lever 23 fastened to the rock 35 shaft 21 is connected by a link 24 to a hand operated lever, 25 which is provided with a spring pressed latch designed to engage the teeth of a segment 26 along which it swings when the lever is rocked. This is 40 a well known adjusting lever construction, the latch serving to maintain the lever in its adjusted position. It is obvious from an inspection of Fig. 2 that as the lever 25 is swung forward or backward, it will 45 move the shafts 8 and 14 forward or backward in their bearings and thus adjust the cams carried by these shafts relatively to the valve stems which they operate, with the results above described.

50 The supply of fuel to the inlet valves may be varied by the throttle 27, Fig. 1, in the usual manner and the adjustment of the throttle may be either independent of or connected with the adjusting mechanism for the valve operating means. In the arrangement shown a rod 28, connected at one end to the throttle 27 and at its opposite end adjustably fastened by the connector 29 to the link 24, enables the operator to adjust the throttle simultaneously 55

with the adjustment of the valve operating mechanisms.

It will readily be appreciated that this arrangement affords an exceedingly flexible control for the engine and reduces the wear and tear on the valve mechanism at low speeds while providing the very large valve opening desirable in order to operate the engine at high speeds or whenever its maximum power is required. It is obvious that 70 the valve opening is multiplied very substantially between the adjustment which permits the minimum flow of fuel to each cylinder and that which permits a maximum flow of fuel. The engine shown operates as a two valve per cylinder engine while producing a relatively small percentage of its maximum power, and as a four valve per cylinder engine while producing a high percentage of its maximum 75 power.

It will also be understood that the disclosure herein made is intended rather by way of explanation than limitation and that the invention may be embodied in many 80 forms while still retaining its essential features and characteristics.

What is claimed as new is:

1. In an internal combustion engine having a plurality of valves controlling the admission of fuel to each cylinder, means for supplying fuel to said valves, operating mechanism for said valves constructed and arranged for adjustment while the engine is in operation to vary the length of stroke 95 of the valves, and manual controlling means common to said fuel supply and said operating mechanism.

2. In an internal combustion engine having a plurality of inlet valves for each cylinder, operating mechanism for said valves constructed and arranged normally to operate one valve only of each cylinder but arranged for adjustment to enable the operator to increase at will the length of 100 stroke of said valves and thereafter to bring another valve into operation in each cylinder when the first valve has substantially 105 reached its maximum stroke.

3. In an internal combustion engine having a plurality of inlet valves for each cylinder, operating mechanism for said valves constructed and arranged for adjustment while the engine is in operation to vary the number of valves in operation in each 110 cylinder and to adjust the length of stroke of said valves, and additional means arranged to be operated simultaneously with said adjustment to vary the supply of fuel to said inlet valves.

4. In an internal combustion engine having a plurality of inlet valves for each cylinder, operating mechanism for said valves constructed and arranged for adjustment while the engine is in operation to vary the 115

stroke of the valves between a fixed minimum and a fixed maximum, said operating mechanism being operative to vary the stroke of one valve without changing the 5 operation of the other valve.

5. In an internal combustion engine having a plurality of inlet valves for each cylinder, operating mechanism for said valves constructed and arranged for adjustment 10 while the engine is in operation to vary the number of said valves in operation in

each cylinder, said mechanism including a hand operated device for effecting said adjustment, and means connected with said device and arranged to be operated thereby 15 simultaneously with said adjustment to effect a predetermined change in the supply of fuel to said inlet valves.

In testimony whereof I have signed my name to this specification.

CHARLES W. E. CLARKE.
